UNITED STATES PATENT OFFICE.

CHARLES McCORMICK, OF RUSSELL, IOWA.

AIR-SHIP.

No. 864,672.

Specification of Letters Patent.

Patented Aug. 27, 1907.

Application filed December 17, 1906. Serial No. 348,245.

To all whom it may concern:

Be it known that I, CHARLES McCORMICK, a citizen of the United States, and a resident of Russell, in the county of Lucas and State of Iowa, have invented certain new and useful Improvements in Air-Ships, of which the following is a specification.

My invention is an improvement in flying machines, being in the nature of a mechanical substitute for a balloon; and the invention consists in certain novel constructions and combinations of parts as will be herein-after described and claimed.

In the drawing Figure 1 is a top plan view of a machine embodying my invention. Fig. 2 is a vertical longitudinal section thereof, and Fig. 3 illustrates a somewhat different construction from that shown in Fig. 2.

By my invention I seek to provide a less expensive, safer, more convenient and less cumbersome device than the ordinary balloon, and by adopting a modification of a parachute I provide what for convenience of reference I call a circular aeroplane A, which may have a canvas or other cover B, and a frame C whose ribs C' divide the circular aeroplane into aeroplane sections, the central ring C² of the frame forming the margin of a central opening D in the aeroplane A, as shown in Figs. 1 and 2 of the drawing. From the frame C, I suspend by suitable hangers E, a suitable motor F, and a car G, the latter being braced by guys H from the outer edge of the frame C, as shown in Fig. 2 of the drawing.

It will be noticed that the aeroplane slopes downwardly from its central opening toward its outer edge and this may be effected on curved lines, as shown in Fig. 2 or straight lines as shown in Fig. 3 and the inclination may be varied as may be desired. A fan or propeller wheel I driven by a motor F is arranged in line with the central opening D and adjacent thereto, being in position to force air outwardly below the under side of the circular aeroplane, as best shown in Fig. 2 in order to exert a lifting tendency as more fully described hereinafter. This propeller I it will be noticed will throw the air outwardly against the under side of the aeroplane A, the axis of the fan being perpendicular and the fan being surrounded with a complete circle of downwardly sloping aeroplane sections, the fan approximating in diameter, the diameter of the central opening, as shown in Figs. 1 and 2.

It will be understood that the air current generated by the fan would on being deflected downward by the curved aeroplane have a tendency to raise the same. Also, this lifting operation will be aided by the elasticity of the air, the fan having a tendency to rarefy the air above the craft and compress the air beneath the craft, in the practical operation of the invention.

To utilize the suction at the poles of the fan and to prevent the current of air from being drawn upward

from beneath the fan, I place a guard in the form of a plate J below the fan and approximately coextensive therewith, as best shown in Fig. 2 of the drawing.

A flexible valve K, which may be of canvas or other suitable material rendered air proof in any ordinary manner is secured at its inner edge to the outer edge of the guard plate J, and extends thence outwardly below the parachute and is connected at its outer edge by hangers K' which may be cords or some flexible connections, as desired, the valve permitting the air to pass outwardly below the aeroplane when the fan is operating and also closing up against the under side of the aeroplane and shutting off the throat leading to the central opening and forming a closed parachute as the apparatus descends, when the fan is stopped and the air presses upwardly against the under side of the parachute.

In connection with the aeroplane A, I prefer to form a top or crown 1 concentric with the aeroplane and having a covering 2 of canvas or the like and being supplied with ribs C¹² similar to the ribs C' of the aeroplane, the outer edge of the top or crown being connected with the outer edge of the aeroplane by cords or wires 3. This top or crown 1 is concave or dished on its upper side, the reverse of the concavity of the aeroplane A, and it operates to add buoyancy and strengthens the entire apparatus. In forming the double concaves, canvas rendered air-tight by any suitable preparation may be utilized and the arrangement of the ribs is such as to form a parachute-like structure as shown.

The basket G it will be noticed is elongated and is located at one end below the center of the concavity, while its other end G' extends out beyond the center so an aeronaut may be seated in the inner end of the craft when it is desired to ride on a level or may transfer his weight toward the outer end of the basket to cause that side of the craft to tip and thus glide off in such direction. The course may be controlled by any suitable form of fan or rudder, and that shown in Fig. 2 may be employed to advantage.

I claim—

1. An air ship comprising a circular aeroplane having a central opening and sloping downwardly therefrom toward its outer edge and having a covering and a frame dividing the covering into a series of aeroplane sections, a fan or propeller wheel in line with said opening and in position to force air outwardly below the under side of the circular aeroplane sections to exert by the downward deflection of the air current below the aeroplane a lifting tendency thereon, a guard plate below and coextensive with said wheel, a flexible valve secured at its inner edge to said guard plate, means suspending the outer edge of the valve from the aeroplane, and a car suspended from the aeroplane, substantially as set forth.

2. In an air ship substantially as described, a circular aeroplane having a central opening and a fan or propeller wheel in line with said opening and in position to force

air outwardly below the under side of the circular aeroplane to exert a lifting tendency thereon, a guard plate below said wheel and a valve connected with said guard plate and controlling the throat between the same and the 5 aeroplane, substantially as set forth.

3. An air ship having a circular aeroplane provided with a central opening and sloping downwardly therefrom toward its outer edge, and a top or dome above said aeroplane and encircling said central opening and sloping 10 upwardly therefrom toward its outer edge, a fan or propeller wheel in line with said opening and in position to force air outwardly below the under side of the aeroplane to exert a lifting tendency thereon, and a guard plate below said wheel, substantially as set forth.

15 4. An air ship having a circular aeroplane provided with a central opening and means for forcing air outwardly below the under side of the circular aeroplane to exert a lifting tendency thereon, and a car suspended from said aeroplane and having one end extended laterally beyond the center of the aeroplane whereby the aeronaut 20

may shift back and forth in the car to control the inclination of the aeroplane, substantially as set forth.

5. An air ship having an aeroplane provided with a central opening and sloping downwardly from said opening toward its outer end, a top or crown sloping upwardly 25 from said central opening of the aeroplane toward its outer edge, and means connecting the outer edge of the top or crown with that of the aeroplane, a fan or propeller wheel below the central opening and in line therewith and in position to force air outward below the under side of the aeroplane to exert a lifting tendency thereon, a guard plate below the fan or propeller wheel, a flexible valve connected at its inner edge with the guard plate and extending thence downward below the aeroplane, and means connecting the outer edge of the flexible valve with 30 the outer edge of the aeroplane, substantially as set forth.
